CLAIM

The ornamental design for a table for an automobile, as shown and described.

DESCRIPTION

FIG. 1 is a perspective view of a table for an automobile, showing my new design;

FIG. 2 is a top plan view;

FIG. 3 is a front elevational view;

FIG. 4 is a side elevational view, the opposite side being a mirror image thereof;

FIG. 5 is a rear elevational view; and,

FIG. 6 is a bottom plan view thereof.
